(57) **CLAIM**

I claim the ornamental design for a grounding tool with locking mechanism for removing spark plug boot, as shown and described.

DESCRIPTION

FIG. 1 is a perspective view of a grounding tool with locking mechanism for removing spark plug boot showing my new design with a cable thereof disconnected for purposes of clarity;

FIG. 2 is an end elevational view thereof;

FIG. 3 is an elevational view of the opposing end thereof;

FIG. 4 is a side elevational view thereof;

FIG. 5 is an elevational view of the opposing side thereof;

FIG. 6 is a top plan view thereof; and,

FIG. 7 is a bottom plan view thereof.

1 Claim, 4 Drawing Sheets

FIG. 7.

FIG. 3.
